UNITED STATES PATENT OFFICE.

JAMES E. KENNEDY, OF WASHINGTON, DISTRICT OF COLUMBIA.

GAS BURNER.

Original application filed October 29, 1921, Serial No. 511,283. Divided and this application filed April 29, 1922. Serial No. 557,256.

To all whom it may concern:

Be it known that I, JAMES E. KENNEDY, a citizen of the United States of America, residing at Washington, in the District of Columbia, have invented certain new and useful Improvements in Gas Burners, of which the following is a specification.

This invention relates to certain new and useful improvements in gas stoves and has particular reference to improved burner constructions for gas stoves, the present application being a division of my copending application Serial Number 511,283 filed October 29, 1921 upon gas stoves.

15 The primary object of the invention is to provide an improved burner construction for gas stoves whereby the same may be conveniently manufactured in considerable quantity at a minimum expense with the 20 resultant product extremely efficient and durable.

With the above general object in view and others that will appear as the nature of the invention is better understood, the invention consists in the novel form, combination and arrangement of parts hereinafter more fully described in connection with the accompanying drawing, in which like characters of reference indicate similar parts 30 throughout the views.

In the drawing,

Figure 1 is a top plan view of the burner, and

Figure 2 is a central transverse sectional view of a burner constructed in accordance with the present invention.

The burner includes a hollow cast body as clearly shown in Figure 1 including a plurality of radial burner members 21 arranged in spaced relation and connected by integral outwardly inclined webs 22, the body being preferably open at the center so as to provide a cylindrical inner wall 23 which also connects the burner members 21, the webs 22 being extended at an outward inclination for the purpose of draining grease or the like as will be apparent from an inspection of Figure 1. The bottom edges of the side walls of the burner members 21 join 50 with the edges of the webs 22, and being similarly inclined, provide comparatively large clearance between the bottom wall 24 and the webs 22 for the instantaneous passage of the gas to all of the burner members 55 21 from the inlet 19 with a minimum ob-

struction, which clearance gradually increases from the outer wall of the burner to the inner wall thereof. The burner members 21 are provided with V-shaped roof or top wall portions which merge with slightly inclined nearly vertical side walls, the lower edges of which connect with the webs 22 and by reason of this particular formation of the burner members practical drainage thereof is insured while the liability of the 60 burner holes 25 becoming clogged is reduced to a minimum, said burner holes being provided in considerable quantity through the top walls of the burner members.

The body of the burner is preferably cast 70 with the bottom open and with the lower margins of the inner and outer walls thereof set at an inclination as clearly seen in Figure 1 so that when the bottom wall 24 has its inner and outer margins flanged over on the 75 lower margins of said walls as at 26, said bottom wall is effectively held to the body portion and with gas-tight joints so that leakage of the gas between the body and bottom members will not occur. In this way, 80 the body portion may be cast without the usual coring operation and the bottom member 24 may be constructed of sheet metal of the desired gage, stamped in disk form with a central opening.

It is believed that the construction and advantages of the present invention will be readily understood and appreciated by those skilled in the art from the foregoing description.

90 Minor changes may be made without departing from the spirit and scope of the invention as claimed.

What is claimed as new is:—

1. A two-piece gas burner including a cast 95 upper section embodying radial burner members having a common inlet and provided with a plurality of burner perforations, said cast upper section having an open bottom and a central opening, and a closing or 100 bottom plate for the bottom of said cast section including a disk of sheet metal provided with a central opening and having its inner and outer margins flanged over the lower margins of the inner and outer walls 105 of said cast section.

2. A two-piece gas burner including a cast 110 upper section embodying radial burner members having a common inlet and provided with a plurality of burner perforations,

2

said cast upper section having an open bottom and a central opening, and a closing or bottom plate for the bottom of said cast section including a disk of sheet metal provided with a central opening and having its inner and outer margins flanged over the lower margins of the inner and outer walls of said cast section, the radial burner members having side walls, the lower edges of which gradually incline outwardly, and outwardly inclined webs having their edges connecting with lower edges of said side walls of the burner members, said burner members

5 having substantially V-shaped top walls.

10 4. A gas burner including a cast upper section having radial burner members connected by outwardly inclined webs and provided with inner and outer walls, the inner 35 wall defining a central opening in the upper section, and a sheet metal disk having a central opening with its inner and outer margins flanged over the inner and outer walls of said upper section into 40 gas-tight contact therewith.

inner and outer margins flanged over the lower margins of the inner and outer walls of said cast section, the radial burner members having side walls, the lower edges of which gradually incline outwardly, and outwardly inclined webs having their edges connecting with lower edges of said side walls of the burner members, said burner members

25

30 having substantially V-shaped top walls.

4. A gas burner including a cast upper section having radial burner members connected by outwardly inclined webs and provided with inner and outer walls, the inner 35 wall defining a central opening in the upper section, and a sheet metal disk having a central opening with its inner and outer margins flanged over the inner and outer walls of said upper section into 40 gas-tight contact therewith.

In testimony whereof I affix my signature.

JAMES E. KENNEDY.
